(57) **CLAIM**

The ornamental design for a detachable hanger as shown and described.

DESCRIPTION

FIG. 1 is an exploded perspective view of a detachable hanger showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is an enlarged view of the portion labelled "8" in FIG. 1;

FIG. 9 is an enlarged view of the portion labelled "9" in FIG. 1;

FIG. 10 is a perspective view of the detachable hanger showing one rod coupled with a sleeve;

FIG. 11 is a perspective view showing the detachable hanger in a fully assembled state; and,

FIG. 12 is a perspective view showing a hanging storage bag coupled to the assembled detachable hanger.

The dash-dash broken lines depicting the hanging storage bag in FIG. 12 is directed to environment only that forms no part of the claimed design. All other dash-dash broken lines depict portions of the detachable hanger that form no part of the claimed design. The encircling dot-dash broken lines in FIGS. 1, 8, and 9 depict reference to the enlargements only and form no part of the claimed design.

1 Claim, 9 Drawing Sheets
